UNITED STATES PATENT OFFICE.

HENRY O. SCHMIDT, OF NEW YORK, N. Y., ASSIGNOR TO SIMONS, BROTHERS & CO., OF PHILADELPHIA, PENNSYLVANIA.

DESIGN FOR A CANE OR UMBRELLA HANDLE.

SPECIFICATION forming part of Design No. 20,557, dated March 3, 1891.

Application filed February 6, 1891. Serial No. 380,616. Term of patent 3½ years.

To all whom it may concern:

Be it known that I, HENRY O. SCHMIDT, a citizen of the United States, residing in New York, in the county and State of New York, have invented and produced a new and original Design for Cane or Umbrella Handles, of which the following is a specification, reference being had to the accompanying drawing, forming part thereof.

10 In the drawing is represented a side elevation of a cane or umbrella handle illustrating my new design.

15 The shank A extends upwardly and terminates on one hand in a crook B and on the other in an upwardly-extending knob C. The top of the crook B is ornamented, as at E. Likewise one side of the shank A is ornamented, as at F. The rest of the shank A

and crook B, as well as the knob C, are made of smooth work. The base of the shank A is 25 ornamented by an annular band D, highly ornamented.

The handle may be made of any suitable material.

Having now described my design, what I 25 claim as new, and desire to secure by Letters Patent, is—

The design for cane or umbrella handles, substantially as herein described and shown.

In testimony of which invention I have 30 hereunto set my hand.

HENRY O. SCHMIDT.
